(57) **CLAIM**

I claim the ornamental design for a faucet handle, as shown and described.

DESCRIPTION

FIG. 1 is a Perspective view of a faucet handle showing my new design;

FIG. 2 is a Front view of the faucet handle as shown in FIG. 1;

FIG. 3 is a Back view of the faucet handle as shown in FIG. 1;

FIG. 4 is a Left-side view of the faucet handle as shown in FIG. 1;

FIG. 5 is a Right-side view of the faucet handle as shown in FIG. 1;

FIG. 6 is a Top view of the faucet handle as shown in FIG. 1; and,

FIG. 7 is a Bottom view of the faucet handle as shown in FIG. 1.

The broken lines shown in the drawings represent unclaimed portions of the faucet handle and forms no part of the claimed design.
